UNITED STATES PATENT OFFICE.

REISSUED

CHARLES A. FOWLER, OF NEW YORK, N. Y.

DESIGN FOR A BREASTPIN.

SPECIFICATION forming part of Design No. 14,502, dated December 25, 1883.

Application filed September 6, 1883. Term of patent 14 years.

To all whom it may concern:

Be it known that I, CHARLES A. FOWLER, of the city, county, and State of New York, have invented a new and original Design for 5 Articles of Mourning-Jewelry, of which the following is a full, clear, and exact description, reference being had to the accompanying drawing, making part of this specification, which drawing represents a front view of a 10 breastpin which fully shows the nature of my invention.

This design relates to an article of mourning-jewelry to which the character of crape is imparted; and the invention consists of a 15 breastpin, or other like article of mourning-jewelry, in which the surface of the body is produced partly in imitation of crape and partly smooth.

In the drawing, A represents a breastpin or

other like article of mourning-jewelry. The 20 front surface of the body is produced partly in imitation of crape, a, and partly with smooth panels b, as shown in the drawing.

Having thus described my design, I claim as new and desire to secure by Letters Patent— 25

The design for a breastpin or other like article of mourning-jewelry, consisting of a body the surface of which is partly in imitation of crape and partly smooth, substantially as shown and described.

In testimony that I claim the foregoing as my invention I have signed it this 31st day of August, 1883.

CHARLES A. FOWLER.
